UNITED STATES PATENT OFFICE.

JACOB STRUBEN, OF KALAMAZOO, MICHIGAN, ASSIGNOR OF ONE-HALF
TO BYRON C. WELLS, OF KALAMAZOO, MICHIGAN.

GLOBE-VALVE.

SPECIFICATION forming part of Letters Patent No. 783,597, dated February 28, 1905.

Application filed May 5, 1904. Serial No. 206,529.

To all whom it may concern:

Be it known that I, JACOB STRUBEN, a citizen of the United States, residing at Kalamazoo, in the county of Kalamazoo and State of Michigan, have invented a new and useful Improvement in a Globe-Valve, of which the following is a specification.

This invention relates generally to globe-valves, and more particularly to certain improvements therein, whereby the valve is made self-grinding upon its seat and also by means of which the valve-spindle can be quickly and easily attached to the threaded stem which raises and lowers said valve.

The invention consists in the novel features of construction hereinafter fully described, and pointed out in the claims.

In the drawings forming a part of this specification, Figure 1 is a vertical sectional view of a globe-valve constructed in accordance with my invention. Fig. 2 is a detail perspective view of the valve and its spindle. Fig. 3 is a detail view showing the lower end of the stem. Fig. 4 is an inverted bottom plan view of the same. Fig. 5 is a sectional view on the line 5-5 of Fig. 1, and Fig. 6 shows the key and wedge in detail.

In carrying out my invention I employ a body portion A, which is provided with the usual threaded ends A' and the threaded neck A², into which screws the bonnet B, said bonnet being provided with the usual construction of gasket-nut C. D indicates the subdividing diaphragm or partition arranged within the body and having the circular horizontal opening D' surrounded by the frusto-conical ring D², which forms the seat for the valve E, the lower face of said valve being recessed, thereby providing a downwardly-extending circular flange E', which overlaps the frusto-conical ring D² and seats thereon, the lower face of the valve resting upon the top of said conical-ring seat, as most clearly shown in Fig. 1. The valve is provided with an integral spindle E², which fits into the externally-threaded stem F, provided with a hand-wheel F' at its upper end, said stem working in the threads carried by the bonnet for the purpose of raising and lowering the valve. The spindle E² is smooth and the bore in which it fits is also smooth, and in order to connect the

spindle and stem I provide a recess G in the side of the spindle adjacent its lower end and into which fits a key H, said key being of a thickness greater than the depth of the recess, 55 so that it projects beyond the face of the spindle and is adapted to fit into an interior recess I, produced in the stem adjacent its lower end, said recess I being slightly wider than the key H, for a purpose hereinafter explained. 60 At the lower end of the stem is produced a transfer dovetailed recess K, into which fits a wedge L, said wedge fitting beneath the lower end of the key H, as most clearly shown, thereby securely connecting the spindle and 65 stem together, so that when the spindle is raised and lowered the valve is also raised and lowered, and by having the recess I slightly wider than the key H a limited amount of play is had between the parts. 70

Having thus fully described my invention, what I claim as new, and desire to secure by Letters Patent, is—

1. The combination with a valve-seat, of a valve adapted to coöperate with the said seat, 75 and having an integral stem, said stem being recessed on one side, an adjustable stem having a longitudinal and a transverse recess, said recesses communicating, said adjustable stem fitting over the integral stem, a key fitting in 80 the longitudinal recess of the adjustable stem, and in the recess of the valve-stem, and a wedge fitting in the transverse recess of the adjustable stem.

2. The combination with a body having an 85 apertured partition, of a frusto-conical valve-seat surrounding said aperture, a valve having a flange adapted to engage said valve-seat, a recessed spindle integral with the valve, a hollow rotatable, and vertically-movable stem 90 adapted to fit over the spindle, said stem being transversely recessed adjacent its lower end and having a communicating longitudinal recess adapted to register with the recess of the spindle, a key adapted to rest in the two 95 last-mentioned recesses, and a wedge adapted to fit the transverse recess of the stem.

JACOB STRUBEN.
